Patented Aug. 3, 1915.

UNITED STATES PATENT OFFICE.

CHARLES M. CALLAHAN, OF WORCESTER, MASSACHUSETTS.

CASKET.

1,148,828.

Specification of Letters Patent.

Patented Aug. 3, 1915.

Application filed April 28, 1909. Serial No. 492,624.

To all whom it may concern:

Be it known that I, CHARLES M. CALLAHAN, a citizen of the United States, residing in Worcester, county of Worcester, and 5 State of Massachusetts, have invented certain new and useful Improvements in Caskets, of which the following is a specification.

This invention is an improvement in caskets, and relates particularly to an attachment or extension to the lining or interior of an ordinary casket, whereby said casket is so changed in appearance as to produce substantially the same effect and appearance as 15 obtains in the so-called full-couch, half-couch, half-shrine, and full-shrine caskets.

Prior to this invention, no attempt has ever been made to extend the lining of the casket loosely over the top edge or surface 20 of the sides and ends and outward to such an extent as to form a valance, which will droop about the outer surfaces of the sides and ends of the casket, thereby doing away with all sharp corners and edges, whereby 25 a soft couch effect is provided.

In the accompanying drawings I have illustrated different practical embodiments of the invention, but the constructions shown therein are to be understood as illustrative 30 only, and not as defining the limits of the invention.

Figure 1 shows the invention applied to an ordinary casket for the purpose of producing a half-couch effect; Fig. 2 shows the 35 invention applied to an ordinary casket for the purpose of producing a full-couch effect; Fig. 3 is a view, partly in section and partly in elevation, on line 3—3 of Fig. 2 (looking in the direction of the arrows), the cover to 40 the casket being off, and the molding on the body being omitted, and showing the extension to the lining dropping over the side of the casket; Fig. 4 is a partial sectional elevation, showing the extension turned back 45 into the casket, the molding on the body being omitted, and showing the position of the cover with reference thereto, and Fig. 5 shows one way of securing the lining and extension together, this view being a partial end elevation, and partial section on line 5—5 of Fig. 1.

Referring particularly to Figs. 1 and 4, A, represents the casket as a whole, b, the side thereof, c, c', the ends, d, the cover, 55 provided with the rail, e, which joins the casket at the top edge, f, thereof. B, is the

ordinary lining common to caskets and extends upwardly to just below the top edge of the sides and ends of the casket. Either made continuous with said lining, *i. e.*, in 60 one piece therewith, or secured thereto by a joining, gimp, milliner's fold, rose trim, or in some other well known or equivalent manner, (such as by blind tacking), is the attachment or extension, C, extending over the 65 edge of the top surface of sides and ends and downwardly, to such extent as desired.

As shown in Fig. 4, the attachment or extension is turned or folded inwardly, and, it will be observed that, in such position, it 70 does not interfere with the locking of the cover in place. In Fig. 4 I have shown extension C secured to lining B; but it will be understood, however, that the extension need not be directly attached, but may be merely 75 tacked to the inside of the casket. This attachment or extension folds loosely, *i. e.* in the flowing manner, over the edge, as described, thereby producing in the depending portion the effect of having a support 80 behind it, as is the case with the couch and shrine caskets previously described. The attachment may extend to the degree desired, *i. e.* merely over the edge, or below the handles so as to cover the same, or to any intermediate point. To produce, *e. g.*, the effect 85 of a "shrine" casket, the extension would drop down lower than though it were desired to produce the "couch" casket effect. The extra lining or filling, g, at the head of 90 the casket is of the ordinary construction for producing the "pillow" effect, and providing for a "shoulder" or "full length" 95 display of body and casket interior.

In Figs. 2, 3, and 5, the casket, as a whole, 95 is designated by, A'; b', is the side thereof, and f', the upper or exposed edge of sides and ends when not covered by the extension. B', is the ordinary lining, and C', the attachment or extension thereto, shown in 100 Figs. 3 and 5 as secured to the lining just below the top edge of casket ends and sides by a gimp, or similar means, h'. The pillow effect at the head of the coffin is substantially the same as shown in Fig. 2 and is 105 designated, g'. When the casket is being brought to the place where it is to be installed, the attachment or extension, C, C', is folded inwardly as shown in Fig. 4, and part of it may, if desired, be tucked into the 110 "cove," or portion just under the rail. It will thus be apparent that the extension does

not in any manner interfere with the placing on, or removing of, the cover of the casket. When the cover has been removed the extension is thrown or folded outward, 5 loosely, into the position shown in Figs. 1, 2, 3, and 5.

In the couch and shrine caskets it requires some little time and trouble to loosen or detach the hinged member or members, 10 usually two or more, to permit of a drop thereof on two sides and one end, or on two sides and two ends, or in such other manner as the design calls for, and, also, requires time and trouble to swing and secure them 15 into their closed positions. It will be observed, moreover, that in the said couch caskets, an unsightly corner is sometimes exposed when the hinged end or ends, and sides, are dropped into their open positions. 20 In my invention, however, no such corner is exposed, but, on the contrary, the same effect is produced on the corners as on the sides and ends, these being continuous and meeting each other without any, or at least any 25 perceptible, joint or union.

In practice, the manufacturer may attach the extension to the lining, and sell the article complete, either affixed to or separate from the casket, or the retailer may, if he 30 prefers, purchase the usual casket lining and attach the extension thereto himself. The extension may be of the same shade or color as the lining, or different, as desired, and, moreover, may be finished on its exposed or 35 outer surface only, or on both surfaces as desired. It will be understood, further, that it may be made of any suitable material, and the lower edge thereof may be finished in any appropriate manner.

40 While the invention is particularly adapted for producing couch and shrine effect caskets, it may be also availed of to cover the exposed corners which now exist in caskets having drop sides and ends.

45 It will be observed that my invention imparts to an ordinary casket the soft, pleasing and couch-like effect so much desired, and that this result is accomplished in a simple and economical manner. Moreover, the ordinary couch and shrine caskets, when closed, do not present an appearance of solidarity, owing to the numerous joints therein, and are more or less objectionable on this account. This objection, it will be 50 apparent, does not apply to the improved casket disclosed herein, and furthermore, the expense and trouble of making the sec-

tional members of the couch and shrine caskets is obviated. Then again, the ordinary casket lining may be applied to the casket 60 more economically and expeditiously, than is now the case, since the tacks or other means employed to secure such lining in place are covered up when the extension occupies its display position, and any defects 65 in the work of fastening said lining are obscured from view.

Throughout the description I have employed the term casket to mean a coffin in addition to what is usually termed a casket. 70

It will be understood, of course, that slight changes may be made in the invention as described, such as the substitution of equivalents, and that it may be adapted to meet various conditions without departing 75 from the spirit or substance of the invention.

Having thus fully described the invention, what I claim as new, and desire to secure by Letters Patent is:

80 1. In a device of the class described, the combination of a burial casket provided with a suitable lining, and a balance secured along one of its edges at the upper edge of the casket so as to normally extend over the 85 upper edge thereof and drape downwardly over the sides of the casket, whereby the unsightly upper edge of the casket is concealed and a neat and pleasing effect produced, said valance being foldable within the casket 90 to allow the close fitting of the casket cover upon the casket.

2. In a device of the class described, the combination of a burial casket provided with a suitable lining, and a valance distinct 95 from and independent of the lining of the casket and secured along one of its edges interiorly of the upper edge of said casket, so as to normally cover said edge of the casket and drape downwardly over the outside of the casket, whereby the unsightly upper edge of the casket is concealed and a neat and pleasing effect produced, said valance being foldable within the top of the 100 casket for the purpose of leaving the upper 105 edge of the casket exposed, whereby a cover may be tightly placed upon the casket.

In testimony whereof I have signed my name to this specification in the presence of two subscribing witnesses.

CHARLES M. CALLAHAN.
